Primary Examiner — Cary M Robinson*Assistant Examiner* — Ezekiel D Bolden(74) Attorney, Agent, or Firm — Banner & Witcoff, Ltd.(57) CLAIM

The ornamental design for a display with graphical user interface of a gaming machine as shown and described.

DESCRIPTION

The FIGURE is a front view of a display with graphical user interface of a gaming machine showing my new design. The broken lines at the perimeter of the figure illustrates the display screen and the remaining broken lines illustrate portions of the graphical user interface. None of the broken lines form part of the claimed design.
